UNITED STATES PATENT OFFICE

JAMES E. GARVIN, OF BATAVIA, NEW YORK

AUTOMOBILE SIGNAL

Application filed March 4, 1931. Serial No. 519,979.

This invention relates to illuminating devices and more particularly to devices lighting the interiors of closed motor vehicles.

Such lighting effects have usually been accomplished by dome lights, acting independent of such signal lights as may be used irrespective of their position.

It is an object of the present invention to provide a single device which will flood the interior of the vehicle with colored light diffused to prevent glare and discomfort to the occupants of the vehicle, and to so arrange this single light as to be utilized as a traffic signal.

15 A further feature is in the provision of a lighting means which renders the several windows on all sides of the car simultaneously luminous, constituting an unusually effective visual signal.

20 Another aim is to focus the light rays on a neutral point, in direct relation to the windows, and which may be steadily shown or flashed intermittently as preferred.

25 A still further object is to provide a lighting device of this character that can be readily applied to vehicles of different types and dimensions.

These several advantageous features are accomplished by the novel construction and arrangement of parts hereinafter described and shown in the accompanying drawing, forming a material part of this disclosure, and in which:—

30 Figure 1 is a partial side elevational, partial longitudinal sectional view of a conventional type of passenger motor vehicle, showing the relation of the improved lighting means.

35 Figure 2 is a longitudinal sectional view of the lamp and its reflector, drawn to an enlarged scale.

40 Figure 3 is a front view of the same.

The type of vehicle seen in Figure 1 indicates six side windows, three on each side, designated by the numerals 5, 6 and 7, a rear window 8 and a front window 9.

45 A steering wheel 10 has its post 11 disposed at an angle to pass through a dash board 12, while therebelow and to one side is a gear lever 13, all of these several parts being old and well established by custom.

Fixed on the dash or instrument board 12 is a switch 14 of any preferred type, controlling current from any convenient source of supply, as a storage battery (not shown), to a lamp 15 set obliquely at an angle of approximately fifteen degrees, in a support 16 secured centrally of the rear wall of the vehicle above the window 8.

A reflector 17 is also mounted in the support 16 and provided with internal screw threads 18 at its outer annular edge, as best seen in Fig. 2, where it will be seen that the reflector also acts as a lens holder.

A cup shaped lens, generally designated by the numeral 20, is provided with a cylindrical base 21 having threads to engage within the combined reflector and lens holder 17, its outer, dome-shaped portion being shaped to present a plurality of facets 23 which constitute light diffusing elements whereby the light rays from the incandescent lamp bulb 15 are broken into numerous needle like rays.

The diffusing lens 20 is preferably made of colored glass, red being the prevailing color, and it will be readily understood that light rays are displayed outwardly from all the windows of the vehicle simultaneously.

By vibrating the switch 14 the rays may be flashed intermittently, attracting attention of persons in all direction from the vehicle, making a fourway signal visible in the day or night.

It will be obvious that the colored signal may be used for night parking purposes in an unmistakable manner.

It will also be evident that a combined lens holder and reflector, together with a diffusing lens, might be adapted for use with an ordinary dome light.

Therefore although a specific embodiment of invention has been shown and described, various modifications may be resorted to within the spirit and scope of the appended claim.

Having thus described the invention, what is claimed as new and desired to secure by Letters Patent, is:—

The method of giving a visual traffic signal from a vehicle having window openings in the body portion thereof, which comprises

providing the vehicle body with means for producing a colored light therewithin, and flooding the interior of the said vehicle body with colored light when it is desired to attract attention thereto, said light being externally visible through the several window openings of the said vehicle.

5 In testimony whereof I have hereunto affixed my signature.
